Attorney.

UNITED STATES PATENT OFFICE.

THEODORE B. TERTELING, OF DETROIT, MICHIGAN, ASSIGNOR TO LION MACHINE COMPANY, OF DETROIT, MICHIGAN, A CORPORATION OF MICHIGAN.

VENDING-MACHINE.

1,024,870.

Specification of Letters Patent.

Patented Apr. 30, 1912.

Application filed April 21, 1911, Serial No. 622,453. Renewed March 16, 1912. Serial No. 684,221.

To all whom it may concern:

Be it known that I, THEODORE B. TERTELING, a citizen of the United States, residing at Detroit, in the county of Wayne and State of Michigan, have invented certain new and useful Improvements in Vending-Machines, of which the following is a specification.

My invention relates to improvements in vending machines, and is primarily designed and adapted for use as a vending machine for matches put up in "penny size" match boxes.

The primary object of the invention is to provide a generally improved vending machine of exceedingly simple, cheap, durable, and efficient construction, better adapted to its intended purposes than any other device of the same class with which I am acquainted.

With the above mentioned and other objects in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Figure 1, is a perspective view of a vending machine constructed in accordance with my invention. Fig. 2, a similar view, with the front plate and delivery hood removed for the purpose of clearer illustration of the parts. Fig. 3, an enlarged cross sectional view of the manually operated rotatable shaft showing the construction and arrangement of the cam and ratchet head, together with the coin engaging arms carried by said shaft. Fig. 4, an enlarged detail view of the face plate and the coin actuated plunger member illustrating the arrangement and relative position of the parts during the passing of the coin or penny.

Similar numerals of reference designate like parts throughout all the figures of the drawings.

The improved vending machine comprises a casing 1, preferably of rectangular form and supported upon a base 2, provided with a receiving trough or channel 2^a, at the front. The box or casing 1, is provided at

its front with a removable face plate or wall 3, said face plate or wall being open at its lower portion for the reception and discharge of the match boxes and provided with a box delivery hood or chute 4, extending over the delivery opening and above the plane of the box receiving trough or channel 2^a. The removable plate 3, is adapted to be suitably secured within the casing 1, and may be locked therein by means of a suitable lock 5.

As a means for suitably storing and feeding the contained match boxes 6, whereby a single match box will be engaged and delivered by the delivery device during each actuation or operation through the medium of a coin and the coin actuated device as hereinafter described, a plurality of box 7, containing partitions 7^a, are provided within the casing, said partitions being provided with vertically arranged box retaining flanges 7^a, at their front, and box supporting flanges 8, at their bottom. The box supporting flanges 8, are adapted to carry the tier of superposed match boxes, and as a means for providing means for the delivery of the lowermost box in the tier, said box supporting flanges 8, are spaced apart to form an intermediate slot 8^a extending from front to rear and the box retaining flanges terminate a sufficient distance above the front ends of the box supporting flanges to form an opening corresponding in form and size to the form and size of the box to be delivered, and through which opening the box is adapted to be ejected as herein-after described.

As a means for successively engaging and ejecting the lowermost box in each tier supported between the respective partitions 7, a rotatable shaft 9, is mounted in the casing below the partitions, said shaft being provided with a plurality of spirally arranged box engaging arms 10, said arms being adapted when the rotatable shaft is manually operated to successively engage and eject the lowermost box in the respective overhanging tier by coming in contact with the rear end of said box, and ejecting the same through the opening in front by passing through the respective slot 8^a, above, the box when so ejected being adapted to be

deflected by the hood 4, and delivered into the receiving trough 2^a.

The rotatable shaft is adapted to be manually operated by means of an operating knob 11, at one side of the casing, and as a means for preventing the active or operative rotation of the latter except through the medium of a coin, a coin chute 12, is arranged within the casing, said coin chute 10 extending from a coin slot 13, and terminating at its bottom in a face plate 14, said face plate being provided with a vertical arm receiving slot 15, and a coin guide member 16, at one side of said slot and offset 15 from the face plate to correspond with the thickness of the coin.

The coin device comprises a coin actuated plunger member 17, consisting, in the present instance, in a plate provided with a 20 nose or projection 17^a, normally extending across the arm receiving slot 15, and a coin receiving beveled or wedge-shaped portion 17^b, adapted to initially receive the coin 18, and support the same in engagement with 25 the coin guide member 16, as the coin falls from the chute 12, above, as illustrated most clearly in Fig. 2, of the drawings.

As a means for holding the coin device or plunger member in proper position and 30 enabling the same to be operated only through the passage of the coin, said plunger member is provided with a main slot 19, and a lateral or branch slot 19^a, said plate or plunger member 17, being supported by means of guide pins or screws 20, on which the slots 19, and 19^a, are adapted to be slidably mounted, and as a means for 35 resiliently holding the plunger member 17, whereby the same may assume the position 40 shown in Fig. 4, during the passing of the coin, and whereby when the coin has passed the plate or plunger member 17, will be returned to its normal position indicated in Fig. 2, coiled springs 21, are secured at opposite corners of the plate or plunger member 17, and connected to pins 22, on the face plate 14, and coin guide member 16.

As a means for permitting the manual operation of the rotatable shaft 9, through 50 the medium of the knob 11, and the downward passage of the coin through the operation of the coin device as above described, a plurality of coin engaging arms 23, are provided at one end of the shaft 9, said 55 arms being arranged in alinement with each other at the rear of the slot 15, and being adapted to be successively rotated and passed out through the slot 15, whereby to initially engage the coin and press the same 60 downward as indicated in Figs. 2, and 4, and as a means for normally holding the shaft in its neutral position, as well as preventing the opposite or rearward movement of the same, a cam and ratchet head 24, is 65 provided (see Fig. 3,) said head being pro-

vided with ratchet toothed portions 24^a, and intermediate recessed portions 24^b, adapted to be brought into coöperative relation with a pivotally mounted dog or pawl member 25, said pivotally mounted dog 25, being mounted on a suitable support 26, and resiliently held in engagement with the parts 24^a, and 24^b, during the rotation of the shaft 9, by means of a spring 27.

From the foregoing description, taken in 75 connection with the accompanying drawings, the operation and advantages of my invention will be readily understood.

Having thus described an embodiment of my invention, what I claim and desire to 80 secure by Letters Patent is,—

1. A vending machine, comprising a face plate provided with a vertical slot, a coin chute adapted to discharge a coin in front of said slot, a plunger member provided 85 with a projection extending in front of said slot and a coin receiving wedge-shaped portion at the side thereof said plunger member being also provided with a main and lateral slot, guide pins carried by said face 90 plate and extending into said main and lateral slots, springs for holding said plunger in its normal position, and a rotatable shaft provided with arms adapted to be projected through the vertical slot in said 95 face plate in coöperative relation to said plunger member and coin chute.

2. A vending machine, comprising a casing, a face plate provided with a vertical slot, a coin chute terminating above said slot, a coin actuated plunger member in coöperative relation to said slot and chute, a rotatable shaft having arms adapted to pass through said slot in coöperative relation to said plunger member, means for preventing the rearward rotation of said shaft 100 and means for locking said plunger member as against the forward rotation of said shaft when no coin is played.

3. A vending machine, comprising a casing, a face plate provided with a vertical slot, a coin guide member, a plunger member provided with guide slots and projecting in front of said slot, a rotatable shaft having arms adapted to be projected through 115 said slot and to engage said plunger member when no coin is played, guide pins co-operating with said guide slots for locking said plunger member as against actuation by said arms and for releasing the same 120 when a coin is played, and means for preventing the rearward movement of said shaft.

4. A vending machine, comprising a casing, a rotatable shaft provided with coin engaging arms, a coin chute carried by said casing and terminating in a face plate provided with a vertical coin arm receiving slot, a coin guide member on said plate at 125 the side of said slot, a coin actuated plunger 130

member extending in front of said slot and provided with guide slots, guide pins extending through and coöperating with said guide slots for locking said plunger member as against direct actuation by said engaging arms, and means for manually rotating said rotatable shaft.

In testimony whereof I have affixed my signature in presence of two witnesses.

THEODORE B. TERTELING.
